UNITED STATES PATENT OFFICE.

CARLOS HOLLY, OF LOCKPORT, NEW YORK, ASSIGNOR TO F. N. BURT COMPANY, LIMITED, OF BUFFALO, NEW YORK, A CORPORATION OF CANADA.

HEAD-FEEDING MECHANISM.

1,180,040.

Specification of Letters Patent.

Patented Apr. 18, 1916.

Application filed February 12, 1912. Serial No. 677,215.

To all whom it may concern:

Be it known that I, CARLOS HOLLY, a citizen of the United States, residing at Lockport, in the county of Niagara and State of New York, have invented certain new and useful Improvements in Head-Feeding Mechanism, of which the following is a full, clear, and exact description, such as will enable others skilled in the art to 10 which it appertains to make and use the same.

This invention relates to box machines, and with respect to its more specific features, to that portion of a box machine 15 adapted to supply and deliver heads to the mechanism for assembling the elements of the box.

One object of the invention is the provision of an efficient mechanism for supporting a plurality of box blanks in convenient position and delivering them successively from such position.

Another object is the provision of a practical feeding mechanism to deliver the box 25 blanks or heads in an accurate manner so as to conform with other mechanism adapted to operate thereon.

Still another object is the provision of efficient guiding and pressing devices to 30 operate with the devices to which the heads are fed and insure the exact positioning of the heads on the latter.

The invention accordingly consists in the 35 features of construction, combinations of elements and arrangement of parts which will be exemplified in the construction hereinafter set forth, and the scope of the application of which will be indicated in the following claims.

In the accompanying drawings, wherein similar reference characters indicate similar parts throughout the several views, Figure 1 is a side elevation of the mechanism, partly broken away; Fig. 2 is a rear view thereof; Fig. 3 is a plan view thereof; Fig. 4 represents a vertical transverse section through the magazine; Fig. 5 represents a longitudinal vertical section; Fig. 6 is a vertical section showing operating parts of the device; Fig. 7 is a plan corresponding to Fig. 6; Fig. 8 is a longitudinal vertical section through a portion of Fig. 7; Fig. 9 is a vertical sectional view of the mechanism showing the associated carrier; and Fig. 10 is a transverse vertical section show-

ing certain associated co-operating mechanism.

The invention forming the subject-matter of this application is disclosed in applicant's prior application, Serial No. 492,029, filed April 24, 1909. In said prior application a box is made by assembling a box head and a box flange in predetermined position, folding the flange around the head, pasting the ends of the flange together, and pasting an extension of the flange to the bottom of the head to secure the head and flange together. The head and flange are assembled on a form carrier comprising a hub 210 having a plurality of radial arms 211 arranged equidistant about the hub, the carrier being secured with its hub to a horizontal shaft 212 journaled transversely in a bearing on the adjacent parts of the main frame A and rotated intermittently by any suitable mechanism so that it comes to rest at intervals with one of its arms projecting vertically upward, and the others disposed at other positions for purposes not here required to explain. The mechanism disclosed to accomplish the intermittent rotary movement of the carrier comprises a mutilated pinion 213 mounted on a countershaft 206 and provided on one-half of its periphery with gear teeth while the remaining half is plain and concentric, and a mutilated gear wheel 214 secured to the outer end of the rotatable carrier-shaft and provided equidistant on its periphery with four toothed segments or sections which are adapted to be engaged successively by the toothed portion of the pinion 213 and four locking faces alternating with the toothed sections and adapted to be engaged successively by the plain concentric locking face of the pinion, the relative size and construction of this pinion and gear wheel being such that the gear wheel is turned one-quarter of a rotation by the pinion during each complete rotation of the latter and the rotatable carrier is held at rest after each quarter step forward to permit of feeding a box head to the carrier, and carrying the head to the flange for assembly therewith.

At its outer end each carrier arm is provided with a form, former, mandrel or block 217, preferably of rectangular shape, upon which the head is received, the block being preferably constructed to serve as a pneumatic gripper and having channels 219 com-

municating with a passageway 220 in the carrier arm, which passageway is at intervals placed in communication with an exhaust device. The head is fed from the 5 magazine to the face of the former or block, and the outer edge of a front jaw 242, arranged transversely at the front edge of each former and mounted on the outer arm of a rock lever 243 on the carrier arm, projects 10 outwardly beyond the face of the former so as to operate as a gage or shoulder with which the front edge of the head engages while the same is being pushed from the bottom of the stack upon the former, the 15 operation of the machine serving to move the jaw 242 into gaging position when the former is in receiving position relative to the heads in the magazine.

The blanks or box heads B delivered to 20 the former are preferably rectangular in shape and composed of paper, pasteboard, etc., as set forth in the prior application, and are supplied from a stack contained in an upright magazine which is arranged in 25 the upper front part of the machine and which preferably consist of two upright side walls 193 adapted to engage with opposite side edges of the heads, a pair of upright inner flanges or shoulders 194 arranged on the rear ends of the side walls and adapted to engage with the front edges of 30 the box heads, and two upright inner shoulders 195 at the front ends of the side walls which are adapted to engage with the rear edges of the box heads, and a bottom 35 196 which extends across the lower end of the magazine and supports the stack of heads therein. The heads are fed or removed successively from the bottom of the 40 stack, in a predetermined path, or plane by means of a delivery device which preferably consists of a horizontally and longitudinally-reciprocating plunger or follower composed of two sections 197 which are arranged side by side and guided in grooves 45 198 in the upper side of the magazine bottom, each section being provided with a rearwardly-facing shoulder 199 at its rear end and a cross piece 200 connected with the 50 front ends of the plunger sections. In its retracted position, the plunger is arranged with its shoulders in front of the stack of heads in the magazine and upon moving the same rearward, these shoulders engage with 55 the rear edge of the lowermost head in the magazine and push the same rearwardly from the bottom of the stack and out through an opening or throat which is formed at the lower rear end of the magazine 60 and which is of such height that it permits only one head at a time to be ejected rearwardly from the magazine. After the plunger or follower has thus removed the lowermost head from the stack, it is returned 65 to its foremost position with its shoulders in

front of the stack, permitting the latter to drop and bring the next following lowermost head in position relatively to the follower to be removed thereby. The forward movement of the follower is effected by 70 means of a spring 201 connected at one end with the side of the cross piece of the follower and at its opposite end with a stationary part of the machine, and the backward movement of the follower is effected 75 by means of an upright elbow lever 202 pivoted on the adjacent part of the frame and having an upper arm which is connected by a link 203 with a horizontally and longitudinally sliding bar 204 connected 80 with the follower crosspiece, and a rotatable cam 205 engaging with the lower arm of the lever 202. The cam 205 is secured to the shaft 206 which is journaled in bearings on the adjacent part of the frame and is 85 driven through a chain wheel 209 secured thereto. On account of the spring means for effecting the discharging movement of the follower, the feed of the blanks from the magazine is in a yielding manner, such 90 yielding favorably qualifying any tendency to crush or bend the blanks, and substantially avoiding fracture of the machine should any obstruction or foreign object be accidentally presented to the mechanism. 95

As the box heads are discharged successively from the under side of the stack in the magazine, they are carried one at a time rearwardly, downwardly, forwardly and upwardly in a circular path and each assembled with a flange strip and binder strip, as hereinbefore explained. Each of the formers is carried into a position in rear of the head magazine at the same time that a box head is being discharged from the magazine, whereby this head is delivered on top of the respective former which at this time has its face arranged uppermost. Immediately after the head has been thus delivered upon the former from the magazine, the air 100 grooves of the former and its respective branch passage are connected with the air, exhaust device, causing the box head to become pneumatically attached to the gripping face of the former. As the box heads 105 are fed from the lower end of the stack in the magazine, the same are guided and pressed downwardly against the face of the former which at this time is moving into position in rear of the outlet of the magazine 110 for receiving the same, thereby insuring reliable attachment of this head to the former by means of the external air pressure which is produced by connecting the air passages of this former with the air exhausting device immediately after the former comes to rest in rear of the magazine outlet. The preferred form of guiding and pressing device for this purpose consists of a horizontal blank pressing and deflecting roller 236 ar- 115 120 125 130

ranged transversely in rear of the outlet of the magazine with its lower part normally intersecting the path of the head which is being discharged from the magazine, two vertically movable rods 237 which carry opposite ends of the pivot of the presser roller, upright guides 238 for said rods mounted on the adjacent stationary part of the machine, and springs 239 arranged in pockets within said guides and each engaging at its upper end with the bottom of said pocket and at its lower end with a shoulder on the respective guide rod for yieldingly holding the roller in its lowered position and restraining or yieldingly resisting movement of the roller away from the opening through which the blank is pressed against the former. An adjustable stop 240 is employed for limiting the downward movement of each guide rod consisting preferably of a screw nut applied to the upper threaded end of said rod and adapted to bear against the upper end of the respective guide. As the lowermost head of the stack is fed or discharged rearwardly from the magazine, its front edge engages with the under side of the guiding and pressing roller 236 and is directed downwardly by the same against the face of the former below the same which former moves in or opposite the opening adjacent the path of movement of the blanks from the magazine which opening, in the present instance, is formed by the guides 231 on the supporting frame. When the paper or stock from which the head is made is comparatively thin and straight, one of such guiding and pressing rollers will suffice to properly direct the heads against the faces of the formers and cause the same to adhere thereto, but when the stock from which the heads are made is comparatively thick and uneven, it is desirable to employ more than one of such guiding and pressing rollers, so as to insure proper attachment of the same to the formers, and to permit of using more than one such rollers a plurality of pairs of guide rods and associated springs and guides are provided upon which extra pressing rollers may be mounted one behind the other, a pair of such extra supporting devices being shown in the drawings one in front and one in rear of the guiding and pressing roller and its supporting devices which have just been described. For the purpose of preventing lateral displacement of the box heads while being fed from the magazine to the formers, two side guides 241, 241 are provided the same being arranged on opposite sides of the path of the heads in rear of the magazine in position to be engaged by the lateral edges of the box heads and supported on the adjacent stationary part of the machine, the box heads being delivered by the feeding mechanism into the space or opening between the guides 241, through which opening they are pressed by the roller 236, onto the carrier. As each box head is fed from the magazine upon the face of a former, the front edge thereof engages with the stop or gage 242 at the front edge or side of the respective former, which will then be in position, as previously explained.

In connection with the magazine it is to be observed that the side walls have basic slotted ears 1, whereby they may be adjustably secured to the supporting frame or bottom plate by means of bolts 2, enabling them to be adjusted to accurately fit the blanks and properly align the same with the devices to which the blanks are to be delivered. Preferably the front shoulders 195 of the side walls are adjustably secured thereto as by screw and slot connection 195' to place the blanks of the stack in proper position relative to the stroke of the plunger device. The throat or delivery opening 3, of the magazine is preferably located adjacent the bottom plate, and in the present instance comprises a gage plate 4, located intermediate the side walls of the magazine and adjustably fastened to a cross piece or supporting bar 5, in turn adjustably secured to the side walls. The shoulders 194 terminate short of the bottom or base by at least the thickness of a blank.

As many changes could be made in the above construction and many apparently widely different embodiments of this invention could be made without departing from the scope thereof, it is intended that all matter contained in the above description or shown in the accompanying drawings shall be interpreted as illustrative and not in a limiting way. It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In a device of the character described, in combination, a magazine comprising a bottom plate, upright side walls adjustably secured in spaced relation to each other on said bottom plate, a supporting bar adjustably fastened to the side walls, a gage plate secured to the supporting bar between the walls and adapted to be adjusted toward and from the bottom, the side walls having spaced relatively adjustable shoulders adapted to guide the blanks.
2. In a device of the character described, in combination, a frame provided with an opening for the passage of blanks, means adapted to support blanks, means adapted to move blanks from said support toward

- said opening, and spring-pressed roller means adapted to press said blanks through said opening.
3. In a device of the character described, 5 in combination, a support, a blank magazine comprising upright side walls secured to the support in spaced relation, means providing a delivery opening in the magazine adjacent the support, said support provided with an 10 opening to which the blanks are delivered, and yielding roller means to guide and press the blanks through the opening.
4. In a device of the character described, 15 in combination, a support, a blank magazine comprising upright side walls secured to the support in spaced relation, means providing a delivery opening in the magazine adjacent the support, said support provided with an opening to which the blanks are 20 delivered, and an elastically mounted roller located over the opening adapted to guide the blank into the opening.
5. In a device of the character described, 25 in combination, a support, a blank magazine, comprising upright side walls secured to the support in spaced relation, means providing a delivery opening in the magazine adjacent the support, said support provided with an opening to which the blanks are 30 delivered, and yielding roller means to guide and press the blanks through the opening, said roller means being carried by the support.
6. In a device of the character described, 35 in combination, a base, parallel grooves therein, upright guide walls projecting therefrom on opposite sides of said grooves, a cross-piece, parallel blank supporting plunger sections engaging said grooves and 40 adjustably connected to said cross-piece, a reciprocating rod guided on said base and connected to said cross-piece, a spring connected to said cross-piece and adapted to move the same to move said plunger sections in the direction to deliver blanks from 45 between said guide walls, a cam, and operative devices between said cam and said rod, whereby motion is positively communicated to said rod to move said plunger 50 sections in the opposite direction.
7. In a device of the character described, 55 in combination, yielding means adapted to feed a blank in a predetermined path, means providing an opening for the passage of the fed blank adjacent said path, and yielding means adapted to deflect said blank into said opening.
8. In a device of the character described, 60 in combination, means adapted to move a blank in a predetermined path, means providing an opening for the passage of the fed blank adjacent said path, a roller arranged to deflect said blank toward said opening, and resilient means adapted to restrain movement of said roller from said 65 opening.
9. In a device of the character described, 70 in combination, yielding means adapted to feed a blank in a predetermined plane, and yielding means intersecting said plane arranged to deflect said blank away from said plane while being fed.
10. In a device of the character described, 75 in combination, means adapted to move a blank in a predetermined path, a deflector comprising a rotatable member normally disposed to intersect said path, and means adapted to yieldingly resist movement of said deflector from said normal position.
11. In a device of the character described, 80 in combination, means adapted to move a blank in a predetermined path, a deflector comprising a rotatable member normally disposed to intersect said path, spring means adapted to yieldingly resist movement of 85 said deflector from said normal position, and stop means adapted to limit the movement of said member by said spring.
12. In a device of the character described, 90 in combination, yielding means adapted to move a blank in a predetermined path, a deflector comprising a rotatable member normally disposed to intersect said path and to be contacted by said blank while being fed, and spring means adapted to yieldingly 95 resist movement of said deflector from said normal position.
13. In a device of the character described, 100 in combination, yielding means adapted to move a blank in a predetermined path, a deflector comprising a rotatable member normally disposed to intersect said path and to be contacted by said blank while being fed, spring means adapted to yieldingly resist movement of said deflector from said 105 normal position, and stop means adapted to limit the movement of said member by said spring.

In testimony whereof I affix my signature, in the presence of two witnesses.

CARLOS HOLLY.
